FIG. 1 is a front view of a twirling figurine toy showing our new design;

FIG. 2 is a side view thereof;

FIG. 3 is a rear view thereof; and

FIG. 4 is a top view thereof.

The opposite side is identical to the side illustrated in FIG. 2 and the bottom of the support is plain.

The dominant features of the invention reside in the portions shown in solid lines.

We claim:

The ornamental design for a twirling figurine toy, substantially as shown and described.
